(57) **CLAIM**

The ornamental design for a game disk case, as shown and described.

DESCRIPTION

FIG. 1 is a front, top and right perspective view of an embodiment of a game disk case showing our new design, the case being opened;

FIG. 2 is a rear, bottom and left perspective view of the embodiment, the case being opened;

FIG. 3 is a top plan view of the embodiment, the case being opened;

FIG. 4 is a bottom view of the embodiment, the case being opened;

FIG. 5 is a front view of the embodiment, the case being opened;

FIG. 6 is a rear view of the second embodiment, the case being opened;

FIG. 7 is a right side view of the embodiment, the case being opened;

FIG. 8 is a left side view of the embodiment, the case being opened;

FIG. 9 is a front, top and right perspective view of the embodiment, the case being closed;

FIG. 10 is a top plan view of the embodiment, the case being closed;

FIG. 11 is a bottom view of the embodiment, the case being closed;

FIG. 12 is a front view of the embodiment, the case being closed, a rear view being a mirror image;

FIG. 13 is a right side view of the embodiment, the case being closed; and,

FIG. 14 is a left side view of the embodiment, the case being closed, a dotted line showing the new design.
